UNITED STATES PATENT OFFICE.

CHARLES S. CASE, OF LESTERSHIRE, NEW YORK, ASSIGNOR TO UNITED SHOE MACHINERY COMPANY, OF PATERSON, NEW JERSEY, A CORPORATION OF NEW JERSEY.

BLOCK-HANDLING DEVICE.

1,129,071.

Specification of Letters Patent. Patented Feb. 23, 1915.

Application filed November 15, 1912. Serial No. 731,560.

To all whom it may concern:

Be it known that I, CHARLES S. CASE, a citizen of the United States, residing at Lestershire, in the county of Broome and State of New York, have invented certain Improvements in Block-Handling Devices, of which the following description, in connection with the accompanying drawing, is a specification.

10 This invention relates to machines for cutting sheet material, such as leather for use in the manufacture of boots and shoes, and more particularly to machines for working upon heavy material, such as sole leather, in which it is necessary to employ a cutting block or bed of considerable size and weight. In machines of this character the working face of the block becomes scarred and worn by the action of the die, so that it is necessary frequently to change the position of the block in order to obtain a smooth and even cutting surface, or to remove the block entirely from the machine for the purpose of planing its working face or in order 20 to substitute another block. At the same time it is important that the block, when in working position, should rest upon a rigid support, such as a stationary part of the framework of the machine, and be secured 25 against lateral movement, in order to oppose unyielding resistance during the cutting operation. In previous machines of this character it has been necessary for the operator, in moving the block, to grasp it and lift it 30 bodily from the support, an operation attended with considerable inconvenience and difficulty.

35 The object of the present invention is to provide in a machine of the character specified, means for facilitating the turning or removal of the block.

The invention is illustrated as embodied in a sole cutting machine but it will be understood that it is applicable broadly to all 40 machines of similar character in which it is necessary at times, to remove or change the position of the cutting block.

In the drawing, which represents in elevation a sole cutting machine having certain 45 portions broken away to show more clearly my improvement applied thereto, 1 indicates the cutting block and 2 the beam that reciprocates above the block and on its descent engages the die or dies to effect the cutting 50 operation in the manner characteristic of

this type of machine. The block 1 rests upon the fixed support 3 which is formed in the present instance with a flat bed plate 4 for supporting equally all portions of the block.

For the purpose of raising the block and changing its position, I have provided the turn table 5 which is located beneath the block and in the form of the invention shown is countersunk in the face of the bed plate 4, with its upper face normally in the same plane as the face of the bed plate, in order that all portions of the block may be supported equally when in working position. The turn table is provided preferably 60 with projections 6 for engaging the lower face of the block to prevent the block from turning with respect to the turn table when supported thereon and is swiveled upon the end of a screw 7 that turns in the support 3 and is provided with a hand wheel 8. When it is desired to change the position of the block the operator turns the screw 7, thereby raising the turn table sufficiently to clear the block from the supporting means. 65 Since the turn table turns freely upon the end of the screw, the block may then be swung easily to any position and lowered again upon the bed plate. For the purpose of facilitating the removal of the block from 70 the machine I have provided the roller 9 which is located preferably on the front of the bed plate and projects slightly above its face. When it is desired to remove the block, the latter is first swung to the dotted 75 line position by the means previously described. By tilting the front end of the block downwardly upon the roller, and using the roller as a fulcrum the block may then be freed from contact with the turn 80 table, and by aid of the roller readily removed from the machine without friction and without the necessity for lifting the block entirely clear of the machine during 85 the process of removal. By a reversal of 90 these operations, the block may be returned to the machine or a new block substituted.

The particular structure herein disclosed is what I regard as the preferred embodiment of my invention, but it will be understood that the invention may be embodied in various other forms of structure within the spirit and scope of the claims.

Having described my invention, what I claim as new and desire to secure by Letters 105

Patent of the United States is the following:

1. In a machine of the character described, the combination with a block and a support arranged to be engaged by the lower surface of the block when the block is in working position, of means for raising the block from engagement with the support, said means being constructed to permit the block when thus raised to be turned readily to different positions with respect to said support. 55
  2. In a machine of the character described, the combination with a block and a support constructed and arranged for engagement with the block, of a turn table located beneath the block and vertically movable to raise the block from contact with the support. 15
  3. In a machine of the character described, the combination with a cutting block and a support arranged to be engaged by the lower surface of the block, of a turn table located beneath the block and vertically movable to raise the block from contact with the support, said turn table having projections for engaging the lower surface of the block to increase frictional resistance to relative turning movement of the block and turn table. 25
  4. In a machine of the character described, the combination with a cutting block and a support arranged to be engaged by the lower surface of the block when the block is in working position, of a turn table located beneath the block and vertically movable to raise the block from the support, and means for raising the turn table. 30
  5. In a machine of the character described, the combination with a cutting block and a support therefor, of a turn table located beneath the block with its upper surface substantially in the plane of the support when the block is in working position, said turn table being vertically movable to raise the block from the support, and a screw for raising the turn table. 40
  6. In a machine of the character described, the combination with a cutting block, of a bed plate for supporting the block, and a vertically movable turn table countersunk in the bed plate, the upper face of the turn 50
- table being normally in the same plane as the face of the bed plate, whereby all portions of the block when in working position may be equally supported. 55
7. In a machine of the character described, the combination with a cutting block, of a bed plate for supporting the block, a turn table countersunk in the bed plate, and means for raising the turn table to lift the block from the bed plate. 60
  8. In a machine of the character described, the combination with a cutting block, of a bed plate for supporting the block, a turn table countersunk in the bed plate, and a screw for raising the turn table from the bed plate, the turn table being swiveled upon the end of the screw. 65
  9. In a machine of the character described, the combination with a cutting block and a support for the block, of means for raising the block and permitting it to swing to different positions with respect to the support, and an anti-friction device on the front of the support coöperating with the turn table 75 to facilitate the removal of the block from the machine. 70
  10. In a machine of the character described, the combination with a cutting block and a support for the block, of a vertically movable turn table for raising the block and permitting it to swing to different positions with respect to the support, and a roller on the front of the support coöperating with the turn table to facilitate the removal of the block from the machine. 80
  11. In a machine of the character described, the combination with a cutting block and a bed plate for supporting the block, of a turn table located in the bed plate, means for raising the turn table to lift the block from the bed plate, and a roller on the machine in front of the bed plate coöperating with the turn table to facilitate the removal of the block from the machine. 90

In testimony whereof I have signed my name to this specification in the presence of two subscribing witnesses.

CHARLES S. CASE.
